FOREIGN PATENT DOCUMENTS

GB 2198348 A 6/1988

Primary Examiner — Karen S Acker*Assistant Examiner* — Clare Ann Gannon(74) *Attorney, Agent, or Firm* — Husch Blackwell LLP(57) **CLAIM**

The ornamental design for an evacuation blanket, as shown and described.

DESCRIPTION

FIG. 1 is a top perspective view of the design of an evacuation blanket;

FIG. 2 is a top plan view of the evacuation blanket shown in FIG. 1; and,

FIG. 3 is a bottom plan view of the evacuation blanket shown in FIG. 1.

Any features shown in broken lines depict environmental subject matter only and form no part of the claimed design.
